APPARATUS FOR DISPENSING AND
INSCRIBING TAPE

Louis D. Walker, Lakewood, Ohio

Application January 12, 1946, Serial No. 640,977

12 Claims. (Cl. 281—11)

1

This invention relates to novel apparatus and method of dispensing and inscribing tape which is desired to be used for labeling packages and articles for shipment, identification, and like purposes.

Heretofore it has been common in the labeling of articles and packages, for such purposes, to avail of tape which may be provided with adhesive for securing the same to the package or other article, and which may be provided in the form of a roll or other suitable condition for handling. The former practice has been to tear off a suitable length of the tape to be used as a label in the particular instance, and then to suitably inscribe the length of tape, which has thus been severed from the main body, with the address of the shipper and consignee, or other identifying indicia, depending upon the purpose for which the labels are to be used.

Such former practice has been unsatisfactory since the dispensing of the tape was not easily handled in this manner, and a table or desk had to be provided to serve as a writing surface on which severed lengths of tape to be used as labels could be inscribed.

Tape dispensing apparatus has heretofore been provided whereby a suitable length of tape was dispensed mechanically and then torn off to be inscribed after severing. It is also recognized that various forms of autographic register means or apparatus such as illustrated in United States Patent No. 1,621,985 for dispensing a piece of paper from a roll and for facilitating the inscribing thereof as dispensed, have been heretofore provided. Such apparatus, however, does not deal with the problem which I have found to exist in connection with the tape intended to be used for labeling articles and packages. In this connection it is to be noted that the labeling of the articles or packages requires use of labels of many different sizes so that where the nature of the articles to be labeled is very diverse, such as, for instance, where very small mechanical parts requiring a label as small as $\frac{1}{2}$ " in length are desired to be labeled at one moment, and much larger packages are desired to be labeled for shipment the next moment, it is not feasible to provide apparatus which dispenses a standard size of label.

It is therefore a principal object of the invention to provide a more efficient method and apparatus for facilitating the dispensing and inscribing of tape intended to be used for labeling purposes, having in mind the peculiar requirements in this connection.

2

An important feature of the invention, in so far as the apparatus is concerned, involves the provision of a movable writing surface, and means for causing a tape to be disposed upon said surface as the latter is moved, the movement of said writing surface causing the labeling tape to be disposed upon said surface in condition to be inscribed while the tape is in contact with said surface.

10 In carrying the invention into practice, I provide means for connecting the labeling tape to the movable writing surface whereby the tape so connected will be dispensed by movement of said writing surface.

15 In the embodiment of the invention herein disclosed I provide an adhesive labeling tape in the form of a roll, and means for rotatively supporting said roll of adhesive tape, the tape having one surface coated with an adhesive sub-

20 stance which preferably requires no moistening or wetting in order to cause it to adhere to any surface with which it is pressed into contact. The free end of this adhesive labeling tape is adapted to be adhesively connected to the movable writing surface, whereby, upon movement of said writing surface the labeling tape so adhesively connected thereto, is caused to be unrolled and disposed upon the writing surface in condition to be inscribed while in contact therewith.

25 To assist in producing this result, I provide means in the form of a roller positioned adjacent the movable writing surface for engaging adhesive tape so connected to said movable writing surface as the tape is unrolled by movement of said surface, and pressing the tape into adhesive connection with the surface.

30 I further provide, in connection with the apparatus, adjustable cutting means, whereby, after a suitable length of labeling tape has been unrolled and disposed upon the movable writing surface by movement thereof and inscribed while in contact therewith, such desired length of labeling tape may be severed from the roll by lifting the tape from the movable writing surface into contact with the cutting means.

35 Means are also provided for imparting movement to the movable writing surface and for adjustment of the means for pressing the labeling tape into adhesive contact with the movable writing surface. In the embodiment of the invention herein disclosed, the means for supporting the roll of adhesive tape comprises slotted guide bearings for supporting the ends of the 40 roll or spindle, whereby the same may be con-

veniently and easily emplaced and withdrawn when the labeling tape has been unrolled therefrom.

A form or method of dispensing and inscribing labeling tape, in accordance with my invention, comprises connecting such a tape to a movable writing surface, moving said writing surface, and causing the tape so connected to be disposed upon the writing surface as the latter is moved, in condition to be inscribed while the tape is in contact with said surface. The method further comprises inscribing the labeling tape while in contact with the movable writing surface and severing the portion of tape so inscribed.

My method and machine, in another aspect, involves the dispensing of a tape having a pressure sensitive adhesive on one side thereof, connected by pressing the adhesive side in contact with a pulling dispensing member or surface, which need not be a writing surface, if inscribing of the tape is not required.

Other objects and advantages of the invention will become apparent from the following description taken in conjunction with the accompanying drawings, in which:

Figure 1 is a longitudinal sectional view illustrating one embodiment of the apparatus of my invention.

Figure 2 is a top plan view of the apparatus illustrated in Figure 1.

Figure 3 is a sectional view taken about on the line 3—3 of Figure 1.

Figure 4 is a sectional view taken about on the line 4—4 of Figure 1.

Figure 5 is a sectional view taken about on the line 5—5 of Figure 1.

Figure 6 is a sectional view taken about on the line 6—6 of Figure 1.

Figures 7 and 8 are detail views of the cutting means and provisions for adjustment of the same, Figure 7 being in section.

Now referring to the drawing, and describing the embodiment of the apparatus there shown, in detail, the numeral 1 indicates a casing adapted to enclose a supply of labeling tape and to substantially enclose the movable writing surface with the exception of that portion thereof which is exposed to permit inscribing the labeling tape disposed thereon. The movable writing surface indicated by the numeral 2 comprises an endless belt preferably of flexible or resilient material such as leather or the like. The belt or movable writing surface 2 is turned over rollers 3 and 4 mounted upon spindles 5 and 6, respectively, the ends of which spindles are emplaced in suitable bearing openings provided in the side walls 7 and 8 of the casing 1. The side wall 8 is removably securable to the remainder of the casing 1 by means of bolts 9 for facilitating the assembling of the ends of the spindles 5 and 6 in the bearing openings provided in the side walls 7 and 8 of the casing. The rollers 3 and 4 are preferably made of rubber or other suitable resilient material for better frictional engagement with the belt or movable writing surface 2. A crank 10 may be operatively connected to the spindle 6, as shown, whereby to rotate a roller 4 and thereby impart movement to the writing surface 2. The side members 7 and 8 of the casing 1 are provided with projecting slotted guide brackets 11 having socket portions 11a for receiving the ends of the spool 12 upon which the roll of labeling tape 13 is wound. By the provision of the slotted guide bearing elements 11 the spool 12 contain-

ing the roll of tape 13 may be easily placed in position rotatably supported by said guide bearing elements, and the spool may readily be removed therefrom when the labeling tape 13 has been completely unrolled therefrom. To facilitate the emplacing of the spool 12 and the roll of tape 13 a top or cover element 14 on the casing 1 is hinged as at 15 to the remainder of the casing.

Mounted to the side members 7 and 8 of the casing and positioned above the belt 2 adjacent the roller 3 is a roller means 16 which is adapted to cooperate with the portion 13a of the labeling tape being unrolled from the spool said roller means 16 acting to press the portion 13a of the tape into engagement with the writing surface 2 as the latter is moved over the rollers 3 and 4 in a clockwise direction, having reference to Figure 1. The roller means 16 comprises a roller 17 rotatably mounted on brackets 18 pivotally connected as at 19 to the side walls 7 and 8 of the casing. Offstanding inwardly from the side walls 7 and 8 of the casing are lugs 20 suitably threaded for the reception of adjusting screws 21, the lower ends of which are threadingly connected to the pivoted brackets 18 whereby the brackets may be adjusted upwardly or downwardly around their pivots by adjustment of the screws 21 for adjustment of the tension with which the roller 17 may engage the tape 13a with the writing surface 2.

The above mentioned labeling tape 13 is preferably an adhesive tape having its underside 13b, namely, the side which is adapted to be brought into contact with the movable writing surface 2, coated with an adhesive substance which does not require that it be moistened or wetted in order to cause it to adhere to the movable writing surface when brought into contact therewith. This type of adhesive coating is preferably of such a nature that it will remain in adhesive connection with any surface with which it is placed in contact, for an indefinite period, yet which will permit the adhesive tape to be disengaged from the surface with which it has been adhesively connected without tearing of the tape in the course of such disengagement. This type of adhesive coating may be referred to as a permanently re-contact sensitive adhesive coating; that is, a coating which remains permanently in re-sensitive condition to cause adhesion upon re-contact.

A supporting or backing element 22 is carried by the side members 7 and 8 of the casing 1 in a position to engage the underside of the belt 2 so as to support that portion of the writing surface 2 which is exposed for access from without the casing 1. The purpose of this backing element 22 is to provide additional support for that part of the writing surface 2 in contact therewith and upon which is disposed the portion 13c of the labeling tape to be inscribed; in order to facilitate inscribing of the labeling tape while it is in contact with the surface 2.

The casing includes an inclined portion 23 upon which is mounted cutting means, the details of which are illustrated in Figures 7 and 8. This cutting means comprises a knife blade 24 having a cutting edge 24a, the knife blade 24 being adjustably mounted to the inclined portion 23 of the casing. For the allotted purpose, the knife blade 24 is provided with slots 24b through which are adapted to extend adjusting screws 25, on which are mounted plates or washers 26 engaging the blade 24. The slots 24b enable the blade to be adjusted both vertically and laterally relative

to the inclined portion 23 of the casing when the adjusting screws 25 are unloosened, and after such adjustment the screws 25 may be tightened so as to maintain the knife blade 24 in the desired position of adjustment. The inclined position of the knife blade 24 is most effective to facilitate the clean severance of the desired portion of the labeling tape to be used as a label after it has been inscribed.

In the use of the apparatus of the invention, the free end 13d of the adhesive labeling tape is unrolled from the spool 12 and adhesively connected to a portion of the movable writing surface 2 adjacent the roller 3. Thereupon, the crank 10 is operated to rotate the roller 4 to move the writing surface 4 in a clockwise direction over the rollers 3 and 4, having reference to Figure 1. This causes the labeling tape to be unrolled from the spool 12 and to be disposed upon the writing surface 2 into position to be inscribed while in contact therewith. The roller means 16 serves to cause the portion 13a of the labeling tape to be pressed into firm and smooth engagement and adhesive connection with the movable writing surface 2 as the labeling tape is unrolled from the spool 12 by movement of the movable writing surface 2. When a suitable length 13c of the labeling tape has been dispensed by being disposed in a position upon the movable writing surface in which it is accessible to be inscribed from a position outside of the casing, movement of the writing surface 2 will be stopped and the exposed portion 13c of the labeling tape will be inscribed by writing thereon with a pen or pencil while the labeling tape is supported by the movable writing surface 2 which is in turn additionally supported by the backing element 22 thus facilitating the inscribing operation.

It will be apparent that in the foregoing manner only the desired length of labeling tape which is intended to be used for a label of predetermined desired size, will be exposed beyond the position of the knife blade 24 into condition to be inscribed. When that portion of the labeling tape which is to be used for the particular label has been disposed in the manner indicated, and suitably inscribed, it will now be severed from the remaining supply of labeling tape by lifting the portion 13c thereof from the writing surface 2 to disengage it from adhesive connection therewith, and thereby engage the labeling tape with the cutting edge of the knife blade 24 to sever the portion 13c from the remaining supply of labeling tape.

Under some conditions, when the tape 13 is to be used after the manner of an ordinary adhesive tape (not for labeling but merely as an adherent connecting web), the belt or surface 2 will act as a pulling member to which the tape will be connected by pressure adhering contact produced by the roller 17. When the tape 13 is dispensed by pulling action of the member 2, it may be merely torn off and applied to articles by secondary pressure of its adhesive surface as a connecting or sealing tape.

Having thus described my invention, what I claim as new and desire to secure by Letters Patent of the United States is:

1. Apparatus of the class described for dispensing and inscribing labeling tape, comprising, in combination, a movable writing surface comprising an endless belt, a supporting member over which the belt passes and supportingly cooperable with a portion of the belt on which the tape is to be disposed, means for causing move-

ment of said surface, and means for causing a labeling tape to be disposed upon said surface as the latter is moved, movement of said surface causing the said tape to be disposed upon said surface in condition to be inscribed while in contact therewith.

2. Apparatus of the class described for dispensing and inscribing labeling tape, comprising, in combination, a movable writing surface comprising an endless belt, a supporting member over which the belt passes and supportingly cooperable with a portion of the belt on which the tape is to be disposed, means for causing movement of said surface, means for imparting movement to said writing surface, and means for connecting a labeling tape to said writing surface as the latter is moved, the movement of said surface causing the tape so connected to be disposed upon said surface in condition to be inscribed while in contact therewith.

3. Apparatus of the class described for dispensing and inscribing labeling tape, comprising, in combination, a movable writing surface comprising an endless belt and a supporting member over which the belt passes and supportingly cooperable with the portion of the belt on which the tape is to be disposed, means for causing movement of said surface, with an adhesive labeling tape positioned adjacent said surface for pressing said tape into adhesive connection with said belt as the latter is moved, whereby movement of said surface will cause said tape so connected to be disposed upon said surface in condition to be inscribed while in contact therewith.

4. Apparatus of the class described for dispensing and inscribing labeling tape, comprising, in combination, a movable writing surface comprising an endless belt, a supporting member over which the belt passes and supportingly cooperable with a portion of the belt on which the tape is to be disposed, means for causing movement of said surface, means for causing a labeling tape to be disposed upon said surface as the latter is moved, movement of said surface causing the said tape to be disposed upon said surface in condition to be inscribed while in contact therewith, and cutting means for severing a portion of the labeling tape from the main body thereof, said cutting means being arranged adjacent the point of entrance of the tape onto the movable writing surface so as to sever the portion disposed on the writing surface from the main body of the tape.

5. Apparatus of the class described for dispensing and inscribing labeling tape, comprising, in combination, a movable writing surface comprising an endless belt, means for imparting movement to said surface, a supply of adhesively coated labeling tape coated with a permanently re-contact sensitive adhesive substance, means cooperable with said tape and positioned adjacent said surface for pressing said tape into adhesive connection with said surface as the latter is moved, movement of said surface causing said tape to be disposed in adhesively connected relation to said surface in condition to be inscribed while so disposed, and means cooperable with the portion of said writing surface upon which the tape is so disposed for rigidifying that portion of said surface.

6. Tape dispensing apparatus comprising, in combination, a frame, a pair of roller members rotatably mounted on said frame, an endless belt passing about said roller members in frictional

engagement therewith, means associated with one of the roller members for causing rotation thereof and consequent movement of said endless belt around said roller members, and means cooperable with an adhesively coated tape coated with a permanently recontact sensitive adhesive substance, and positioned adjacent said belt for pressing said tape into adhesive connection with said belt as the latter is moved, whereby movement of said belt will cause said tape to be disposed upon said belt in tight adhesive connection therewith.

7. Tape dispensing apparatus comprising, in combination, a frame, a pair of roller members rotatably mounted on said frame, an endless belt passing about said roller members in frictional engagement therewith, means associated with one of the roller members for causing rotation thereof and consequent movement of said endless belt around said roller members, means for rotatably supporting adjacent said belt, a roll of adhesively coated tape coated with a permanently recontact sensitive adhesive substance, and tension roller means comprising a roller member positioned adjacent to said belt for pressing said tape into adhesive connection with said belt as the latter is moved, whereby movement of said belt will cause said tape so connected to be disposed upon said belt.

8. Tape dispensing apparatus comprising, in combination, a frame, a pair of roller members rotatably mounted on said frame, an endless belt passing about said roller members in frictional engagement therewith, means associated with one of the roller members for causing rotation thereof and consequent movement of said endless belt around said roller members, means for rotatably supporting adjacent said belt a roll of adhesively coated tape coated with a permanently recontact sensitive adhesive substance, and tension roller means comprising an arm pivoted to said frame, a roller member pivotally mounted on said arm, and adjusting means carried by said frame and cooperating with said arm, said roller member being positioned adjacent said belt for pressing said tape into adhesive connection with said belt as the latter is moved, whereby movement of said belt will cause said tape so connected to be disposed upon said belt in tight adhesive connection therewith, said adjusting means being adjustable to alter the position of the roller member relative to said belt.

9. Tape dispensing apparatus comprising, in combination, a frame, a pair of roller members rotatably mounted on said frame, an endless belt passing about said roller members in frictional engagement therewith, means associated with one of the roller members for causing rotation thereof and consequent movement of said endless belt around said roller members, means for rotatably supporting adjacent said belt a roll of adhesively coated tape coated with a permanently recontact sensitive adhesive substance, and tension roller means comprising an arm pivoted to said frame, a roller member pivotally mounted on said arm, and adjusting means carried by said frame and cooperating with said arm, said roller member being positioned adjacent said belt for pressing said tape into adhesive connection with said belt as the latter is moved, whereby movement of said belt will cause said tape so connected to be disposed upon said belt in tight adhesive connection therewith, said

adjusting means being adjustable to alter the position of the roller member relative to said belt, and cutting means arranged adjacent the point of entrance of the tape onto said belt, said cutting means being operable to sever the portion of tape disposed on said belt from the main body of the tape.

10. Apparatus of the class described for dispensing and inscribing labeling tape, comprising, in combination, a frame, a pair of roller members rotatably mounted on said frame, a movable writing surface comprising an endless belt passing about said rollers in frictional engagement therewith, a supporting member over which the belt passes and supportingly cooperable with a portion of the belt on which the tape is to be disposed, means associated with one of the roller members for causing rotation thereof and consequent movement of said endless belt around said roller members, and means cooperable with adhesive labeling tape positioned adjacent said belt for pressing said tape into adhesive connection with said belt as the latter is moved, whereby movement of said belt will cause said tape to be disposed thereon in tight adhesive connection therewith in condition to be inscribed while so disposed on said belt over said supporting member.

11. Apparatus of the class described for dispensing and inscribing labeling tape, comprising, in combination, a frame, a pair of roller members rotatably mounted on said frame, a movable writing surface comprising an endless belt passing about said rollers in frictional engagement therewith, a supporting member over which the belt passes and supportingly cooperable with a portion of the belt on which the tape is to be disposed, means associated with one of the roller members for causing rotation thereof and consequent movement of said endless belt around said roller members, and means for connecting said tape to said surface as the latter is moved, whereby movement of said surface will cause said tape so connected to be disposed upon said surface in condition to be inscribed while in contact therewith over said supporting member.

12. Apparatus as claimed in claim 11, combined with cutting means for severing a portion of the labeling tape from the main body thereof, said cutting means being arranged adjacent the point of entrance of the tape onto the movable writing surface so as to sever the portion disposed on the writing surface from the main body of the tape, said cutting means comprising a blade arranged in a plane at an angle to the plane of the tape disposed upon said writing surface.
